MARKING DEVICE

Courtney R. Lindholm, St. Louis, Mo., assignor
to Independent Die and Supply Company, St.
Louis, Mo., a corporation of Missouri

Application September 12, 1934, Serial No. 743,703

1 Claim. (Cl. 101—287)

This invention relates generally to marking devices for tracing outlines upon the parts of shoe uppers, and particularly to a die for such apparatus.

5 Sections of shoe upper material which are to have portions cut out, or which are to be stitched to other parts, are frequently marked or inked along the lines which are to be cut out or followed so that the operative, when performing the 10 operations upon these sections of upper material, will be guided as to the lines which are to be followed. Apparatus for so marking or tracing sections of upper material is ordinarily provided with a number of dies, each having differently 15 configurated marking edges whereby to trace different configurations upon the sections of upper material.

An object of the present invention, generally 20 stated is to provide a die for a marking machine of the character referred to, and particularly to provide a device for connecting the die to the cooperating parts of such apparatus.

A further object of this invention is to provide 25 a die of the character referred to with a retaining device capable of clamping the die in position under its own resilience.

A more specific object of this invention is to 30 provide a device for connecting a die of the character referred to, to its mounting member by frictional engagement between a resilient stud and a cooperating internal wall in the mounting member.

Other objects will become apparent to those 35 skilled in the art when the following description is read in connection with the accompanying drawing, in which:

Figure 1 is a perspective view of a marking machine of the character referred to and provided 40 with a die and connecting device constructed in accordance with the present invention.

Figure 2 is a longitudinal sectional view taken along line 2—2 Figure 1 and showing the connecting device of the present invention more in detail.

45 Figure 3 is a perspective view of a die plate provided with connecting devices formed in accordance with the present invention.

Figure 4 is a detail sectional view of a securing device employed in accordance with the present 50 invention.

In accordance with the present invention, the die plate of a tracing machine for sections of shoe upper material may be provided with a plurality of upstanding resilient studs and the cooperating member of the machine which takes the die plate

may be provided with recesses arranged to receive the studs on the die. In accordance with the present invention the recesses referred to may be slightly smaller in at least one diameter than are the resilient studs so that when the studs are forced into the recesses, the die is clamped in position by the resilience of the studs against the interior of the recess. This arrangement enables the dies to be removed and replaced with facility and speed, and, at the same time, provides a 10 secure connection without necessitating the operation of any clamps, latches or adjusting devices.

Referring now particularly to the drawing, in Figure 1, a tracing machine of the character referred to is illustrated. Such a machine may comprise a frame 1, having a work receiving bed 2 upon which the sections of upper material to be marked are placed in a predetermined relation to the operating parts of the machine. Such a 20 section of upper material is illustrated in position as shown at 3 upon bed 2, it being understood that suitable provision may be made for locking the section of upper material upon the bed 2.

Upon an elevated portion 4 of the frame 1 may be provided a source of ink supply such as a pad 5 and mounted for oscillation back and forth between the bed 2 and the ink supply 5 is a head 6 which, in the embodiment illustrated, is mounted 30 upon a pair of links 7 at the front thereof and a pair of links 8 at the back. In the embodiment illustrated, the links 7 and 8 are so mounted that when the head 6 is pushed rearwardly it will seat itself upon the inking pad 5 and when it is pulled forwardly it will seat itself upon bed 2, as indicated in dotted lines in Figure 1. For the purpose of oscillating the head 6 back and forth, a suitable handle such as 9 may be provided thereon or the device may be operated by other suitable actuating means.

In order to form the desired markings upon the section of upper material 3, such markings being, for instance, illustrated by the lines 11, a marking die 12 provided with marking edges 110 45 corresponding to the desired configuration may be mounted upon the lower surface of head 6. Since the character of markings which it is desired to place upon the sections of upper material will differ with various lots of shoes, it is important that the die 12 be so connected with head 6 that although it is securely clamped thereto during operation it may be readily removed and replaced with another die when it is 50 55

desired to change the character of markings desired to be applied to the sections of upper material such as 3.

In order to facilitate application, removal and replacement of the dies 12, but at the same time maintain a secure connection between the same and head 6 during operation, the head 6 may be provided with a plurality of recesses 13 which, in the embodiment illustrated, are simply holes through the head. Provided on the surface of die plate 12 opposite the marking edges 110 may be a plurality of studs 14 so located thereon that when they are inserted in the respective recesses 13, the die plate will be properly positioned on the head with reference to the locating devices on bed 2, and the markings 11 will be properly positioned on a section of upper material.

In the embodiment illustrated, the studs 14 may be made hollow, as illustrated clearly in Figure 4, down to near their point of connection with die plate 12. In the embodiment illustrated, the studs 14 are longitudinally slit, as shown at 15, in order to render the same diametrically resilient. One or more such slits may be provided in order to render the stud resilient in one or more diameters. As shown clearly in Figure 4, the studs 14 are provided with a bulged portion 16 in the upper region thereof and it will be understood that such bulged portion is of a slightly greater diameter than the internal diameter of recesses 13 so that when the studs are inserted in the recesses, the stud is diametrically compressed so that a tight frictional engagement is operative to securely hold the die plate 12 in position upon head 6. It will be understood, however, that the stud may be made solid or non-yielding and a suitable resilient bushing provided on the interior of recess 13 for cooperating therewith, or that instead of splitting the studs 14 they may be made sufficiently thin that they will be distorted in at least one diameter when they are inserted in recesses 13 and thus be able to accomplish the necessary

45

frictional contact between the frictional surfaces to retain die plate 12 in position.

From the foregoing description it is apparent that the present invention accomplishes its objects and that a die plate, and particularly a securing device therefor is provided, which permits of ready replacement of die plates of the character described, while providing a sufficiently secure mounting for the plates during operation. Moreover, the connection between the plate 12 10 and head 6 is, in accordance with the present invention, effected automatically—that is to say without necessitating the manipulation of any clamp, latch or adjusting device. To remove the plate 12 from the head 6, an instrument of any 15 suitable type may be inserted between plate 12 and head 6 or may be inserted through the upper open end of holes 13 to force studs 14 from within.

Since it is apparent that many modifications 20 of the marking device hereinbefore described will present themselves to those skilled in the art, it is to be understood that the invention is not limited to the specific details of construction which have been hereinbefore described. It is 25 to be understood, therefore, that such modifications and the use of such individual features and sub-combinations of features as do not depart from the spirit of this invention are, although not specifically described herein, contemplated 30 by and within the scope of the appended claim.

Having thus described the invention, what is claimed is:

A machine for marking shoe uppers comprising in combination, a bed, an ink supply, a head 35 moveable between said bed and said ink supply, said head having a plurality of sockets therein, a die having a plurality of friction studs relatively arranged thereon for engagement respectively with correspondingly disposed sockets in 40 the head, said studs being longitudinally split and diametrically resilient, and said studs being larger in at least one diameter than the socket in the head.

COURTNEY R. LINDHOLM. 45
